United States Patent Office

Des. 185,968

Patented Aug. 25, 1959

185,968

BRANCH HOLDER

Winfield H. Moore, St. Paul, Minn.

Application December 12, 1957, Serial No. 48,887

Term of patent 3½ years

(Cl. D35—1)

FIG. 1

FIG. 2

FIG. 3

I claim:

The ornamental design for a branch holder, as shown.
